UNITED STATES PATENT OFFICE.

GRANT HALSTEAD, OF ORLANDO, NEBRASKA

POST-PULLER.

1,219,303.

Specification of Letters Patent. Patented Mar. 13, 1917.

Application filed September 12, 1916. Serial No. 119,713.

To all whom it may concern:

Be it known that I, GRANT HALSTEAD, a citizen of the United States, residing at Orlando, in the county of Garden and State 5 of Nebraska, have invented certain new and useful Improvements in Post-Pullers, of which the following is a specification.

This invention relates to improvements in devices for pulling posts, and has for one 10 of its objects to provide a simply constructed device whereby fence posts or like devices may be withdrawn from the ground.

With this and other objects in view, the invention consists in certain novel features 15 of construction, as hereinafter shown and described and then specifically pointed out in the claim; and in the drawings illustrative of the preferred embodiment of the invention—

20 Figure 1 is a side elevation of the improved device applied;

Fig. 2 is a detached perspective view of the standard or fulcrum supporting bracket;

Fig. 3 is a detached perspective view of 25 the gripping portion of the improved device;

Fig. 4 is a detached perspective view of the fulcrum block of the improved device.

Corresponding and like parts are referred 30 to in the following description and indicated in all the views of the drawings by the same reference characters.

The improved device comprises a relatively long handle 10 of sufficient strength to 35 withstand the strains to which it will be subjected, the handle may be of any required length, but for ordinary use will be about six feet long. Bearing upon the upper face and the front end of the handle or lever 40 member 10 is a bar formed with a body portion 11, a laterally directed portion 12 and a toe portion 13, the latter terminating in a point 14. The body portion 11 is provided with apertures to receive clamp bolts 45 15 by which the body is secured to the lever 10. Bearing upon the lower face of the lever 10 is a U-shaped hanger or bracket formed with a lower portion 16 and side portions 17—18, the latter having lateral 50 off-sets 19—20 at their outer ends perforated to receive the bolts 15 by which the body 11 is secured in position, the bolts having clamp nuts 21 bearing against the

inner faces of the off-sets 19—20. By this means the bracket device is securely held 55 in position by the same bolts which are employed to secure the body 10 of the post-engaging member. Attached to the portion 16 of the bracket is a fulcrum block, represented as a whole at 22 and preferably 60 relatively long to present a relatively large bearing surface to the ground. The member 22 is preferably recessed, as indicated at 23, to receive the portion 16 of the bracket, and secured thereto by bolts or 65 like devices, indicated at 24.

By this simple means a very strong, compact and powerful lever device is produced which may be employed to pull posts and like devices from the ground, a portion of 70 a post being represented conventionally at 25 and the ground at 26. In employing the improved device the pointed terminal 14 of the lever device is engaged with the post 25 and the fulcrum block 22 engaged 75 with the ground 26, as shown in Fig. 1. Then by exerting a downward force upon the outer end of the lever 10 a powerful lifting force is applied to the post to withdraw it from the ground and if the first 80 movement of the lever is not sufficient to fully remove the post the "nipping" point 14 may be again located at a lower point on the post and the operation repeated. The lever 10 and the block 22 are preferably 85 of wood, while the member 11, together with its depending portion 12 and toe 14 and the bracket, are of metal.

Having thus described the invention, what is claimed as new is:

A device of the class described comprising a stock extended into a handle at one end, a bar including a body portion engaging said stock at the other end and a right angled projection bearing against the adjacent end of the stock, the projection having a reduced extension terminating in a wedge shaped point, a bracket having lateral portions bearing against the stock and secured thereto by fastening devices which likewise pass through the bar, and a fulcrum block attached to the body of the bracket.

In testimony whereof I affix my signature.

GRANT HALSTEAD. [L.S.]
